Claims priority, application Germany Dec. 10, 1955

16 Claims. (Cl. 12—20)

The present invention relates to new improvements in shoemaking machinery and more particularly to a machine for cementing a ribbed sewing or reinforcing strip upon a plane insole or for gluing a reinforcing strip upon an insole which has been provided with a rib which is formed by splitting the insole at the inside or the outside or at both sides thereof.

It is an object of the present invention to provide a single machine which permits both functions to be carried out, namely, to apply a ribbed strip upon a plane insole, as well as to apply a reinforcing strip to a split insole and the rib thereon which is formed by the split portions.

The machines which were known for this purpose prior to this invention operate either with tong arms which are movable relative to each other or with rotating rollers. Other machines known for this purpose have rollers which merely serve for guiding a ribbed strip supplied thereto, while the two lateral web portions thereof are pressed upon the plane insole by means of a mechanism consisting of a hammer and an anvil. Those machines which operate with tong arms have the disadvantage that the insole with the reinforcing or ribbed strip cemented thereon is advanced in a step-by-step movement rather than continuously as with pressure rollers. Such machines operating with tongs also do not permit the reinforcing or ribbed strip to move around an arc of a relatively small radius. This disadvantage is avoided in machines operating with pressure rollers, provided these rollers acting upon the ribbed or reinforcing strip are disposed so that their rotary axes extend parallel to each other. However, such machines operating with pressure rollers as were known prior to this invention could only be used either for applying reinforcing strips upon insoles on which the rib was formed by splitting the insole or for cementing prefabricated ribbed strips upon the insoles. Therefore, it was previously impossible to use only one machine to carry out both of these functions.

For attaining the above-mentioned object of the invention, namely, to provide a machine which permits both functions to be carried out on the same machine, the invention first provides a mechanism for cementing a reinforcing strip upon an insole which is split on the inside or outside or on both sides thereof so as to form a rib consisting of two lips. This mechanism consists of two rotating pressure and feed members which are applied at the same side of the insole, and a reciprocating pressure member for pressing the reinforcing strip upon the surfaces of the rib on the insole, and also for pressing the lateral webs of such strip upon the surfaces of the insole itself. Although a similar mechanism is known for gluing a prefabricated reinforcing strip upon an insole it does not permit any pressure to be exerted upon a rib on the strip in a direction substantially perpendicular to the surface of the insole. Such pressure is also not required in the known machines since the

2

prefabricated ribbed strip to be applied is flat and does not contain or partly enclose a relatively rigid rib.

Another feature of the invention consists in arranging the two rotating pressure and feed members at the same side of the insole so that their rotary axes are disposed perpendicularly to each other, and to design and mount the reciprocating pressure member which is movable in a straight direction so as to be disposed opposite to the pressure and feed member which engages into the space enclosed by the rib so that this reciprocating member will press the web portion on the inner side of the rib against the insole.

Another feature of the invention consists in providing the drive shaft of the rotating pressure and feed member which is disposed outside of the space enclosed by the rib in the form of a hollow shaft, and to mount within said shaft the shaft of a third pressure or pressure and feed member so that the latter projects beyond the other member. The active diameter of this third member is made smaller than that of the surrounding pressure and feed member, and it may be either freely rotatable therein or also be driven. In the latter case it may serve not only as a pressure member but also as a feed member, and the two telescoped pressure and feed members should then be driven so as to have the same peripheral speed, preferably by the same driving shaft by means of bevel gears or the like. These two concentrical members are preferably also mounted so as to be either slidable in their axial direction or to be pivotable, or to be movable in both directions to permit them to be adjusted to various thicknesses of the split portion or the rib formed thereby. Furthermore, in order to facilitate the design and operation of the machine, the shafts of the pressure and feed members which are disposed vertically to each other may be interconnected by an endless belt, for example, a chain, and may both be driven by the same main drive shaft which also operates the reciprocating pressure member. The reciprocatory movement of this pressure member is preferably attained by means of an eccentric which connects the pressure member at least indirectly with the main drive shaft.

Further objects, features, and advantages of the present invention will be apparent from the following detailed description thereof, particularly when read with reference to the accompanying drawings, in which—

Fig. 1 shows a side view, partly in cross section, of a machine according to the invention;

Fig. 2 shows a side view, partly in cross section, of a portion of the machine as shown in Fig. 1;

Fig. 3 shows the driving elements of the machine per se;

Fig. 4 shows diagrammatically the entire driving system of the machine;

Fig. 5 shows a side view, partly in section, of the machine parts which directly act upon the insole and the ribbed strip;

Fig. 6 shows a more enlarged side view, also partly in section of the pressure and feed members acting upon a prefabricated ribbed strip to press the same upon the insole;

Fig. 7 shows a view similar to Fig. 6 in which the pressure and feed members act upon a reinforcing strip to apply the same upon a rib which is formed by splitting the insole at both sides thereof; while

Fig. 8 shows a perspective view of the reciprocating pressure member, the upper part of which entirely surrounds the pressure and feed member which is disposed at the inside of the rib, while the lower part thereof only partly surrounds such member.

Referring to the drawings, the machine frame 1 sup-

ports a main drive shaft 3 which is rotatably mounted thereon, for example, by means of a bearing 2, and carries a worm 4 which is in engagement with a worm gear 5 secured to a shaft 6. This shaft 6 has further secured thereon a gear 7 and a pinion 8. Gear 7 engages with a gear 10 which is freely rotatable on a shaft 9 and secured to a sprocket wheel 11 which is likewise freely rotatable on shaft 9, while pinion 8 engages with a gear 12 secured to shaft 9. The lower end of shaft 9 carries suitable driving means, for example, a sprocket wheel 13, which is connected by an endless power transmitting member, for example, a chain 14, with a driven wheel, for example, a chain wheel 15 which is secured to a shaft 16. The upper end of shaft 16 carries a table 17 which is rotatably mounted on a stationary column 18 by means of a thrust bearing 19.

The power transmitting sprocket wheel 11 is connected by a chain 20 to a sprocket wheel 21 and also to a sprocket wheel 22 so as to drive the same. Sprocket wheel 21 is mounted on the upper end of a shaft 23, the lower end of which carries a bevel gear 24 which engages with another bevel gear 25 secured to a hollow shaft 26. This shaft 26 carries on its other end a suitable pressure and feed member, for example, in the form of a knurled wheel 27 integral with shaft 26. The outer end surface of wheel 27 is slightly conical, and may be more or less inclined relative to the axis of shaft 26, for example, at an angle of 82°, depending upon the shape of the rib or ribbed strip to be applied to the insole. At its lower end, shaft 23 carries a further bevel gear 28 in mesh with a bevel gear 29 which is mounted on a shaft 30, the outer end of which carries a further pressure member or pressure and feed member 31. Shaft 30 and member 31 do not need to be driven, and in such event member 31 only acts as a pressure member upon the rib on the insole or of the prefabricated ribbed strip.

Sprocket wheel 22 is mounted on the upper end of a vertical shaft 32, the lower end of which carries a third pressure and feed member 33 which may, for example, be keyed thereon. One end of the main shaft 3 carries an eccentric 34 having an arm 35 which reciprocates a connecting rod 37 mounted on a shaft 36 which is slidable within the machine frame 1 so as to move upwardly and downwardly in the direction of the arrow 38, as shown in Fig. 1. The lower end of connecting rod 37 carries a fourth pressure member 39 which, by the reciprocating movement of rod 37, hammers upon the inner web of a reinforcing strip or of the ribbed strip to apply the same to the surface 40 of insole 41. The pressure member 39 is secured to connecting rod 37, for example, by a screw 42. By turning a screw 43 which acts upon a stop member 44 it is possible to adjust the bearing members 45 and 46 together with all the parts mounted thereon by pivotal movement about the axis 47 in the direction of arrow 48, as illustrated in Fig. 4. Suitable means, not shown, may also be provided to prevent chain 20 from loosening when members 45 and 46 are being pivoted. In place of the table 17, it is also possible to provide a counterroller 49, as shown in Fig. 5, which may be mounted on a shaft 50 and be driven by shaft 9, for example, by bevel gears, not shown.

Figs. 6 and 7 show enlarged views of the essential parts of the machine according to Figs. 1 to 4 or 1 to 5, respectively, for illustrating that the same may be used either for applying a reinforcing strip on an insole with a rib separate from the insole or with a rib formed by splitting the insole. According to Fig. 6, the insole 41 is provided with a ribbed strip consisting of an upstanding rib 51 and a reinforcing strip 52. This ribbed strip is preferably prefabricated, the strip 52 then being glued fully to the outer and upper surfaces of rib 51 and only partly to the inner surface thereof before the entire ribbed strip is fed to the machine. Since the surface

of rib 51 facing toward the surface of the insole has a fishtail-like shape and the inner web of the reinforcing strip 52 is fed so as to lie at the higher level than the surface of the insole to which it is to be glued, and since 5 the pressure member 39 exerts a pressure upon the inner web of the reinforcing strip in a direction perpendicular to the insole surface, the rib also is strongly pressed against the insole surface and the rib and the webs of the reinforcing strip will be securely glued to each other 10 as well as to the upper surface of the insole. While the ribbed strip is being applied, the pressure and feed member 27 presses the outer web of the strip 52 against the insole and operates at the same time as a back rest to 15 to resist the pressure exerted by the pressure and feed member 33. The pressure or pressure and feed member 31 acts upon the upper edge of rib 51 and assists and supports the attachment of the entire ribbed strip to the insole caused by the downward drawing action of the pressure member 39 upon the inner web of strip 52. For compensating the difference between the rotary 20 speed of the knurled outer surfaces of the pressure and feed members 27 and 31, shaft 30 may be provided with an annular disk 53 which it fitted into member 27. This disk 53 does not have to be secured to shaft 30 but may 25 be freely rotatable thereon.

If the machine as previously described is to be used for applying a reinforcing strip 56, as shown in Fig. 7, upon an insole 54 which has previously been provided with a rib 55 consisting of a pair of lips produced by an inner and an outer cut in the upper surface of the insole, it will be necessary to exchange the pressure and feed member 27 which acts upon the outer web of the strip, as shown, for example, in Fig. 6, for a pressure and feed member 27' which is shaped in conformity with the outer 30 cut and adapted to engage in the recess in the insole formed thereby. Also, the pressure member 39 as shown in Fig. 6 must then be exchanged for a pressure member 39' as shown in Fig. 7 to engage in the recess in the insole at the inner side of rib 55.

Fig. 8 shows a separate perspective view of the pressure member 39 which is adapted to reciprocate in a straight line upwardly and downwardly. Its upper portion surrounds the drive shaft 32 of the knurled pressure and feed member 33, and its lower end is provided with a recess 45 57 which permits member 33 to pass into member 39 and operate freely therein upon the reinforcing or ribbed strip without interfering with member 39, so that within the area of operation of member 33 the pressure member 39 will not engage with and act upon the reinforcing or ribbed strip. However, since pressure member 39 acts upon this portion of the strip in front of and behind member 33, and member 39 is preferably reciprocated upwardly and downwardly at such speed that it hits upon the insole once at every feeding movement of the strip of, 50 for example, 1.8 mm., a perfect connection will be attained also at the inner side of the rib.

While the invention has been described in detail with reference to certain now preferred examples and embodiments thereof, it will be understood by those skilled in the art that various changes and modifications may be made without departing from the spirit and scope of the invention as defined in the appended claims.

The invention having now been fully disclosed, that which is claimed as new is:

65 1. An apparatus for cementing to an insole a strip having a folded central portion projecting from said insole and adapted to receive and cover an elongated element for forming with the same a rib on the upper surface of said insole, comprising a support, two rotary pressure and feed members adapted to be disposed at the same side of said insole on said support and forming an inner and an outer member, each of said members having a drive shaft, said shafts being disposed substantially perpendicularly to each other, said inner member being adapted to 70 engage into the area of said insole surrounded by said

rib and to engage upon the portion of said strip on the inner surface of said rib, said outer member being disposed at the outside of said area and adapted to engage upon said strip at the outer surface of said rib and also upon the strip portion on said insole outside of said rib, a pressure member having a lower portion partly surrounding said inner member and an upper portion fully surrounding the shaft of said inner member and being guided by said shaft for movement relative to said inner member, and means for reciprocating said last pressure member in a straight direction and substantially perpendicularly to said support and to the axis of said outer member for pressing the portion of said strip at the inner side of said rib against said insole.

2. An apparatus for cementing to an insole a strip having a folded central portion projecting from said insole and adapted to receive and cover an elongated element for forming with the same a rib on the upper surface of said insole, comprising a support, two rotary pressure and feed members adapted to be disposed at the same side of said insole on said support and forming an inner and an outer member, each of said members having a drive shaft, said shafts being disposed substantially perpendicularly to each other, the shaft of said outer member being hollow, said inner member being adapted to engage into the area of said insole surrounded by said rib and to engage upon the portion of said strip on the inner surface of said rib, said outer member being disposed at the outside of said area and adapted to engage upon said strip at the outer surface of said rib and also upon the strip portion on said insole outside of said rib, a third rotary pressure member projecting from said outer member and having an active diameter smaller than the active diameter of said outer member and being adapted to engage upon the upper edge of said rib, said third member having a shaft coaxially with and rotatably supported by said hollow shaft of said outer member, a non-rotatable pressure member surrounding said inner member, and means for reciprocating said last pressure member in a straight direction and substantially perpendicularly to said support and to the axis of said outer member for pressing the portion of said strip at the inner side of said rib against said insole.

3. An apparatus for cementing to an insole a strip having a folded central portion projecting from said insole and adapted to receive and cover an elongated element for forming with the same a rib on the upper surface of said insole, comprising a support, two rotary pressure and feed members adapted to be disposed at the same side of said insole on said support and forming an inner and an outer member, each of said members having a drive shaft, said shafts being disposed substantially perpendicularly to each other, the shaft of said outer member being hollow, said inner member being adapted to engage into the area of said insole surrounded by said rib and to engage upon the portion of said strip on the inner surface of said rib, said outer member being disposed at the outside of said area and adapted to engage upon said strip at the outer surface of said rib and also upon the strip portion on said insole outside of said rib, a third rotary pressure member projecting from said outer member and having an active diameter smaller than the active diameter of said outer member and being adapted to engage upon the upper edge of said rib, said third member having a shaft coaxially with and guided by said hollow shaft of said outer member, means for rotating said coaxial shafts so as to rotate said outer and third member at a substantially equal peripheral speed, a nonrotatable pressure member surrounding said inner member, and means for reciprocating said last pressure member in a straight direction and substantially perpendicular to said support and to the axis of said outer member for pressing the portion of said strip at the inner side of said rib against said insole.

4. An apparatus for cementing to an insole a strip having a folded central portion projecting from said insole and adapted to receive and cover an elongated element for forming with the same a rib on the upper surface of said insole, comprising a support, two rotary pressure and feed members adapted to be disposed at the same side of said insole on said support and forming an inner and an outer member, each of said members having a shaft, said shafts being disposed substantially perpendicularly to each other, the shaft of said outer member being hollow, said inner member being adapted to engage into the area of said insole surrounded by said rib and to engage upon the portion of said strip on the inner surface of said rib, said outer member being disposed at the outside of said area and adapted to engage upon said strip at the outer surface of said rib and also upon the strip portion on said insole outside of said rib, a third rotary pressure member projecting from said outer member and having an active diameter smaller than the active diameter of said outer member and being adapted to engage upon the upper edge of said rib, said third member having a shaft coaxially within and guided by said hollow shaft of said outer member, a drive shaft, first gear means on said drive shaft, second gear means on each of said coaxial shafts and in engagement with said first gear means for rotating said coaxial shafts so as to rotate said outer and third members at a substantially equal peripheral speed, a non-rotatable pressure member surrounding said inner member, and means for reciprocating said last pressure member in a straight direction and substantially perpendicularly to said support and to the axis of said outer member for pressing the portion of said strip at the inner side of said rib against said insole.
5. An apparatus for cementing to an insole a strip having a folded central portion projecting from said insole and adapted to receive and cover an elongated element for forming with the same a rib on the upper surface of said insole, comprising a support, two rotary pressure and feed members adapted to be disposed at the same side of said insole on said support and forming an inner and an outer member, each of said members having a shaft, said shafts being disposed substantially perpendicularly to each other, the shaft of said outer member being hollow, said inner member being adapted to engage into the area of said insole surrounded by said rib and to engage upon the portion of said strip on the inner surface of said rib, said outer member being disposed at the outside of said area and adapted to engage upon said strip at the outer surface of said rib and also upon the strip portion on said insole outside of said rib, a third rotary pressure member projecting from said outer member and having an active diameter smaller than the active diameter of said outer member and being adapted to engage upon the upper edge of said rib, said third member having a shaft coaxially within and guided by said hollow shaft of said outer member, a drive shaft, first gear means on said drive shaft, second gear means on each of said coaxial shafts and in engagement with said first gear means for rotating said coaxial shafts so as to rotate said outer and third members at a substantially equal peripheral speed, a non-rotatable pressure member surrounding said inner member, means for reciprocating said last pressure member in a straight direction and substantially perpendicularly to said support and to the axis of said outer member for pressing the portion of said strip at the inner side of said rib against said insole, and endless power-transmitting means connecting said drive shaft with said shaft of said inner member for driving the same.
6. An apparatus for cementing to an insole a strip having a folded central portion projecting from said insole and adapted to receive and cover an elongated element for forming with the same a rib on the upper surface of said insole, comprising a support, two rotary pressure and feed members adapted to be disposed at the same

side of said insole on said support and forming an inner and an outer member, each of said members having a shaft, said shafts being disposed substantially perpendicularly to each other, the shaft of said outer member being hollow, said inner member being adapted to engage into the area of said insole surrounded by said rib and to engage upon the portion of said strip on the inner surface of said rib, said outer member being disposed at the outside of said area and adapted to engage upon said strip at the outer surface of said rib and also upon the strip portion on said insole outside of said rib, a third rotary pressure member projecting from said outer member and having an active diameter smaller than the active diameter of said outer member and being adapted to engage upon the upper edge of said rib, said third member having a shaft coaxially within and guided by said hollow shaft of said outer member, a drive shaft first gear means on said drive shaft, second gear means on each of said coaxial shifts and in engagement with said first gear means for rotating said shafts so as to rotate said outer and third members at a substantially equal peripheral speed, a non-rotatable pressure member surrounding said inner member, means for reciprocating said last pressure member in a straight direction and substantially perpendicularly to said support and to the axis of said outer member for pressing the portion of said strip at the inner side of said rib against said insole, endless chain gears connecting said drive shaft with said shaft of said inner member for driving the same, and eccentric means also connected with said drive shaft for reciprocating said nonrotatable pressure member.

7. An apparatus for pressing to an insole a strip having a folded central portion projecting from said insole and adapted to receive and cover an elongated element for forming with the same a rib on the upper surface of said insole, the apparatus comprising, in combination, supporting means having a supporting face for movably supporting said insole on the bottom surface thereof; two rotary pressure and feed members located opposite said supporting face and adapted to be located on opposite sides of the folded portions of said strip of an insole supported on said support means, the axes of rotation of said pressure and feed members extending transverse to each other, one of said pressure and feed members being adapted to engage the portion of said strip on the inner surface of said rib, and the other pressure and feed member being adapted to engage said strip at the outer surface of said rib and also the strip portion located on the insole outside of the rib; means for rotating said pressure and feed members; and a rotatable pressure roll mounted for rotation relative to said pressure and feed members and having a peripheral surface located opposite said supporting face and adapted to engage the upper edge of said rib for urging said folded central portion of said strip toward said insole.

8. An apparatus for pressing to an insole a strip having a folded central portion projecting from said insole and adapted to receive and cover an elongated element for forming with the same a rib on the upper surface of said insole, the apparatus comprising, in combination, supporting means having a supporting face for movably supporting said insole on the bottom surface thereof; two rotary pressure and feed members located opposite said supporting face and adapted to be located on opposite sides of the folded portions of said strip of an insole supported on said support means, the axes of rotation of said pressure and feed members extending transverse to each other, one of said pressure and feed members being adapted to engage the portion of said strip on the inner surface of said rib, and the other pressure and feed member being adapted to engage said strip at the outer surface of said rib and also the strip portion located on the insole outside of the rib; means for rotating said pressure and feed members; and a rotatable pressure roll mounted

for rotation relative to said pressure and feed members and having an axis of rotation parallel to said supporting face and a peripheral surface located opposite said supporting face and adapted to engage the upper edge of said rib for urging said folded central portion of said strip toward said insole.

9. An apparatus for pressing to an insole a strip having a folded central portion projecting from said insole and adapted to receive and cover an elongated element for forming with the same a rib on the upper surface of said insole, the apparatus comprising, in combination, supporting means having a supporting face for movably supporting said insole on the bottom surface thereof; two rotary pressure and feed members located opposite said supporting face and adapted to be located on opposite sides of the folded portions of said strip of an insole supported on said support means, the axes of rotation of said pressure and feed members extending transverse to each other, one of said pressure and feed members being adapted to engage the portion of said strip on the inner surface of said rib, and the other pressure and feed member being adapted to engage said strip at the outer surface of said rib and also the strip portion located on the insole outside of the rib, said one pressure and feed member having an axis of rotation extending perpendicularly to said supporting face; means for rotating said pressure and feed members; and a rotatable pressure roll mounted for rotation relative to said pressure and feed members and having an axis of rotation parallel to said supporting face and a peripheral surface located opposite said supporting face and adapted to engage the upper edge of said rib for urging said folded central portion of said strip toward said insole.

10. An apparatus for pressing to an insole a strip having a folded central portion projecting from said insole and adapted to receive and cover an elongated element for forming with the same a rib on the upper surface of said insole, the apparatus comprising, in combination, supporting means having a supporting face for movably supporting said insole on the bottom surface thereof; two rotary pressure and feed members located opposite said supporting face and adapted to be located on opposite sides of the folded portions of said strip of an insole supported on said support means, one of said pressure and feed members being adapted to engage the portion of said strip on the inner surface of said rib, and the other pressure and feed member being adapted to engage said strip at the outer surface of said rib and also the strip portion located on the insole outside of the rib, said one pressure and feed member having an axis of rotation extending perpendicularly to said supporting face; means for rotating said pressure and feed members; a rotatable pressure roll having an axis of rotation parallel to said supporting face and a peripheral surface located opposite said supporting face and adapted to engage the upper edge of said rib; a pressure foot member surrounding said one pressure and feed member and having a pressure face confronting said supporting face; and means for moving said pressure foot member in a direction perpendicular to said supporting face for pressing a portion of said strip located inwardly of said rib against said insole.

11. An apparatus for pressing to an insole a strip having a folded central portion projecting from said insole and adapted to receive and cover an elongated element for forming with the same a rib on the upper surface of said insole, the apparatus comprising, in combination, supporting means having a supporting face for movably supporting said insole on the bottom surface thereof; a first rotary pressure and feed roller having an axis of rotation perpendicular to said supporting surface, said first pressure and feed roller being adapted to engage the portion of said strip on the inner surface of said rib; a second pressure and feed roller having an axis of rotation perpendicular to said axis of said first pressure and feed roller,

said second pressure and feed roller having an end face adapted to engage said strip at the outer surface of said rib, and having a circular peripheral face adapted to engage the strip portion located on the insole outside of the rib; means for rotating said first and second pressure and feed rollers; and a rotatable pressure roll mounted for rotation relative to said pressure and feed members and having an axis of rotation parallel to said supporting face and having a peripheral surface adapted to engage the upper edge of said rib for urging said folded central portion of said strip toward said insole.

12. An apparatus for pressing to an insole a strip having a folded central portion projecting from said insole and adapted to receive and cover an elongated element for forming with the same a rib on the upper surface of said insole, the apparatus, comprising, in combination, supporting means having a supporting face for movably supporting said insole on the bottom surface thereof; a first rotary pressure and feed roller having an axis of rotation perpendicular to said supporting surface, said first pressure and feed roller being adapted to engage the portion of said strip on the inner surface of said rib; a second pressure and feed roller having an axis of rotation perpendicular to said axis of said first pressure and feed roller, said second pressure and feed roller having an end face adapted to engage said strip at the outer surface of said rib, and having a circular peripheral face adapted to engage the strip portion located on the insole outside of the rib; means for rotating said first and second pressure and feed rollers including a hollow shaft fixed to said second pressure and feed roller; another shaft located in said hollow shaft coaxial with the same and being turnable in the same; and a pressure roll secured to said other shaft and projecting from said end face of said second pressure and feed roller, said pressure roll having a peripheral surface adapted to engage the upper edge of said rib.

13. An apparatus for pressing to an insole a strip having a folded central portion projecting from said insole and adapted to receive and cover an elongated element for forming with the same a rib on the upper surface of said insole, the apparatus, comprising, in combination, supporting means having a supporting face for movably supporting said insole on the bottom surface thereof; a first rotary pressure and feed roller having an axis of rotation perpendicular to said supporting surface, said first pressure and feed roller being adapted to engage the portion of said strip on the inner surface of said rib; a pressure foot member surrounding said first rotary pressure and feed roller and having a pressure face confronting said supporting face; means for moving said pressure foot member in a direction perpendicular to said supporting face for pressing a portion of said strip located inwardly of said rib against said insole; a second pressure and feed roller having an axis of rotation perpendicular to said axis of said first pressure and feed roller, said second pressure and feed roller having an end face adapted to engage said strip at the outer surface of said rib, and having a circular peripheral face adapted to engage the strip portion

located on the insole outside of the rib; means for rotating said first and second pressure and feed rollers; and a rotatable pressure roll having an axis of rotation parallel to said supporting face and having a peripheral surface adapted to engage the upper edge of said rib.

14. An apparatus as set forth in claim 13 and wherein said means for rotating said pressure and feed rollers includes a shaft supporting said first pressure and feed roller; and wherein said pressure foot member has an annular guide portion slidably mounted on said last-mentioned shaft and surrounding the same whereby said pressure foot member is movably guided on said last-mentioned shaft.

15. An apparatus for pressing to an insole a strip having a folded central portion projecting from said insole and adapted to receive and cover an elongated element for forming with the same a rib on the upper surface of said insole, the apparatus, comprising, in combination, supporting means having a supporting face for movably supporting said insole on the bottom surface thereof; a first rotary pressure and feed roller having an axis of rotation perpendicular to said supporting surface, said first pressure and feed roller being adapted to engage the portion of said strip on the inner surface of said rib; a pressure foot member surrounding said first rotary pressure and feed roller and having a pressure face confronting said supporting face; means for moving said pressure foot member in a direction perpendicular to said supporting face for pressing a portion of said strip located inwardly

30 of said rib against said insole; a second pressure and feed roller having an axis of rotation perpendicular to said axis of said first pressure and feed roller, said second pressure and feed roller having an end face adapted to engage said strip at the outer surface of said rib, and having a circular peripheral face adapted to engage the strip portion located on the insole outside of the rib; means for rotating said first and second pressure and feed rollers including a hollow shaft fixed to said second pressure and feed roller; another shaft located in said hollow shaft coaxial

35 with the same and being turnable in the same; and a pressure roll secured to said other shaft and projecting from said end face of said second pressure and feed roller, said pressure roll having a peripheral surface adapted to engage the upper edge of said rib.

40 16. An apparatus as set forth in claim 15 and including means connected to said other shaft for rotating the same.
